US0D1049598S

(12) **United States Design Patent** (10) **Patent No.:** **US D1,049,598 S**
(45) **Date of Patent:** **** Nov. 5, 2024**

(54) **INSOLE**

(71) Applicant: **Love in Soul (FuJian) Technology Co., Ltd.**, Putian (CN)

(72) Inventor: **Maohua Zhou**, Putian (CN)

(73) Assignee: **Love in Soul (FuJian) Technology Co., Ltd.**, Putian (CN)

(**) Term: **15 Years**

(21) Appl. No.: **29/859,390**

(22) Filed: **Nov. 9, 2022**

(30) **Foreign Application Priority Data**

May 31, 2022 (CN) 202230330070.9

(51) **LOC (14) Cl.** **02-04**

(52) **U.S. Cl.**

USPC **D2/961**; D24/192

(58) **Field of Classification Search**

USPC D2/915, 946, 947, 949, 968, 976,
D2/951-961; D24/192

CPC A43B 13/00; A43B 17/00; A43B 3/00;
A43B 7/00

See application file for complete search history.
